TUBE LUBRICATOR

John W. Kelso, East McKeesport, Pa., assignor to
 National Tube Company, a corporation of New
 Jersey

Application June 28, 1939, Serial No. 281,708

1 Claim. (Cl. 80—11)

This invention relates to the rolling of metallic pipes and tubes, and more particularly to the novel method and apparatus for internally lubricating the same immediately prior to the rolling operation.

In the art of rolling metallic pipes and tubes it has long been conventional to roll the pierced or tubular blank over a plug or mandrel in order to control the internal diameter and also to smooth out the interior surface thereof. This practice has resulted in severe wear on the plug or mandrel and scratches on the interior surface of the blank. The earliest expedient was to station at the inlet side of the mill a man whose duty it was to insert a small quantity of coal dust, salt or other medium in the blank immediately prior to its passage over the plug or mandrel. Due to the highly heated condition of the blank, combustion takes place immediately and, as a result thereof, very little lubricating effect is obtained, and that only for a short distance from the leading or advance end thereof.

Another practice has been to provide mechanism constructed and arranged to introduce lubricant to the plug or mandrel through the bar by which it is supported, but this results in the flow of oil onto the rolls of the mill, thus reducing their tractive power by causing slippage.

It is among the objects of the present invention to provide a novel apparatus for efficiently lubricating the interior of a metallic tubular blank in such manner that the lubricating medium cannot possibly come in contact with the rolls of the mill.

Another object is the provision of means of the type described which may be easily and inexpensively installed on pipe or tube mills of any design, including those now in use.

The invention, then, comprises the features hereinafter fully described and as particularly pointed out in the claim, the following description and the annexed drawing setting forth in detail certain illustrative embodiments of the invention, this being indicative of but one of the number of ways in which the principles of the invention may be employed.

In the annexed drawing:

Figure 1 is an elevation of a pipe or tube mill disclosing in section the metal-working rolls, the entering trough, and part of the blank being processed; while the mandrel, mandrel bar and device of the invention are in section;

Figure 2 is a sectional view on the line II—II of Figure 1;

Figure 3 is a fragmentary elevation illustrating

the position of some of the instrumentalities of the apparatus of the invention during a certain working phase thereof; and

Figure 4 is a view similar to Figure 3 illustrating another working phase.

Referring more particularly to the drawing, the numeral 2 designates a pair of rolls whose axes occupy a common vertical plane, the adjacent portions of the peripheries of the rolls providing a horizontal line of pass. Rolls of this type comprise what is referred to in the art as a "high-mill"; but it will be readily understood that the invention is applicable to all types of pipe or tube mills, including those which advance the blank helically, such as "Mannesmann" or "Steifel" mills.

In the type of rolling referred to hereinabove (i. e. over plug or mandrel), the plug or mandrel, designated herein at 3, is disposed intermediate the rolls 2 and is held in position against thrust by means of a mandrel bar 4 which is suitably supported in any suitable manner (not shown) from a distant point.

At the conclusion of the passage of the blank over the plug or mandrel 3, the mandrel bar 4 lies within the tube. A second pair of rolls of opposite rotation (not shown) but referred to hereinafter as stripper rolls, is disposed on the return side of the mill. These stripper rolls are inoperative during the rolling operation but are brought into action to strip the blank from the mandrel bar 4 and return it to the entering end of the mill. The metal-working rolls 2 are inactive during this phase. After the blank has been returned to the entering side of the mill, it is again passed between the metal-working rolls 2 and the intermediately disposed plug or mandrel 3, thereby duplicating the operating cycle.

The teaching of the invention comprises the injection into the leading end of the workpiece, and while it is on the entering side of the mill, of a suitable lubricant, such as oil or other combustible carbonaceous material. When using oil or other combustible carbonaceous material, its contact with a highly heated tubular blank in insufficient air causes the production of carbon in the form of lampblack which is disposed on the interior surface of the blank. As the blank is engaged by the metal-working rolls 2 and forced over the plug or mandrel 3, the accumulation of lampblack provides the desired lubrication.

Referring more particularly to Figure 1, the numeral 7 designates the entering trough on the entering side of the mill. This entering

trough 7 is shown (see Figure 2) as comprising a pair of downwardly convergent metallic plates, the lower ends of which are spaced to provide an aperture 9. At a point which is adjacent the entry side of the metal-working rolls 2 there is provided immediately beneath the aperture 9 in the entering trough 7 a suitable support shown in the present instance as comprising a pair of parallel spaced beams 12. Each of the spaced beams 12 carries an upwardly extending plate 13 to which there is secured on the adjacent sides thereof aligned bearings 14. Journaled within the bearings 14 is a short rotatable shaft 15 provided with an elongated vertical extension 16 which is adapted to extend into and through the aperture 9 provided by the space between the lower edges of the downwardly convergent plates of the entering trough 7. The extension 16 is provided with an interior bore 17 terminating adjacent the center of the shaft 15 on its inner end and on its outer end terminating in a right angular passage 20 which faces the direction of the feed of the tubular blank as it moves through the entering trough 7. The rotatable shaft 15 is also provided with a downwardly depending portion 22 to which there is connected a tension spring 23. This tension spring 23 is suitably secured in such manner as to bias the upward extension 16 of the rotatable shaft 15 into a truly vertical position.

The rotatable shaft 15 is provided with an axial bore 25. Disposed within the bore 25 of the rotatable shaft 15 is a tube 26 which is secured against rotation, as at 27, to the adjacent upwardly extending plate 13. The tube 26 is provided with a small vertical aperture 28 which is adapted to register with the inner end of the bore 17 of the upward extension 16 of the rotatable shaft 15 when the said extension 16 is in a truly vertical position. When the extension 16 is in other positions, the bore 17 does not register with the aperture 28 in the tube 26 and communication is therefore cut off. This tube 26 is connected by a suitable pipe line 29 to a source of lubricant (not shown). Disposed in the pipe line 29 between the source of lubricant and the tube 26 is a valve 30 which is operated by a solenoid 31 or other suitable device.

The solenoid 31, or equivalent device, is arranged to operate the valve 30 in such manner that the lubricant is admitted to the bore 17 in the upward extension 16 of the rotatable shaft 15 as soon as the workpiece enters the entering trough 7 and to stop the flow of lubricant as soon as the blank contacts the upper end of the extension 16, which is disposed in its path. When there is no blank in the entering trough 7, the tension spring 23 normally holds the extension 16 of the rotatable shaft 15 in truly vertical position; and while in this position the valve 30 is closed by the solenoid, or equivalent device, 31 and no oil flows through the bore 17 of the vertical extension 16 of the rotatable shaft 15; and, accordingly, no oil is ejected through the right angular aperture 20 which forms the nozzle of the ejecting device. Of course, when the vertical extension 16 of the rotatable shaft 15 is in its truly vertical position, communication is established back to the valve 30, as previously described.

In operation:

When the blank, designated at B, starts into

the entering trough 7, the solenoid, or equivalent device, 31 is suitably operated to open the valve 30 wherein the lubricant is permitted to flow and to be ejected from the aperture 20 which forms the nozzle. A spray of lubricant thus enters through the leading end of the tubular blank B. As the blank B is moved towards the metal-working rolls 2, it contacts the upward extension 16 of the rotatable shaft 15 and causes the same to be tripped into the position shown at X in Figure 3. This causes the bore 17 of the upward extension 16 to move out of registration with the vertical aperture 28 in the tube 26, thus shutting off the flow of lubricant.

15 After the tubular blank has moved completely over the upward extension 16 of the rotatable shaft 15, the solenoid, or equivalent device, 31 is operated to close the valve 30, thus shutting off the flow of lubricant to the tube 26. At this 20 time the vertical extension 16 of the rotatable shaft 15 is returned to its original vertical position by the spring 23.

Referring to Figure 4, the letter Y designates the position of the vertical extension 16 of the rotatable shaft 15 while the blank is being returned by the stripper rolls (not shown) to its original position in the entering trough 7. The valve 30 having been closed, and no flow of lubricant permitted to the tube 26, there is, of course, no ejection of lubricant, and the instrumentalities of the invention are inoperative other than the tilting of the upward extensions 16 to the position Y and the stretching of the tension spring 23. When the blank has been moved entirely over the vertical extension 16, it returns to its original position, at which time the solenoid, or equivalent device, 31 is operated to open the valve 30 and repeat the cycle.

While I have shown and described one specific embodiment of the present invention, it will be seen that I do not wish to be limited exactly thereto, since various modifications may be made without departing from the scope of the invention, as defined by the following claim.

45 I claim:

In combination with a pipe or tube mill, a device for lubricating the interior of a tubular blank including a retractable ejector device disposed in the path of the tubular blank in its movement 50 toward the mill, said retractable ejector device comprising a pivoted member extending into the path of the tubular blank and providing a feed orifice, means for supplying a lubricant under pressure to said pivoted member and through 55 said feed orifice, said pivoted member being adapted for movement into its retracted position by contact therewith of the tubular workpiece, means operable by the retraction of said pivoted member for interrupting the supply of lubricant to said feed orifice, means for discontinuing the supply of said lubricant to said pivoted member 60 when the latter is in its retracted position, means for restoring said pivoted member to its unretracted position, said last named means being operable to restore communication of said feed 65 orifice with the lubricant-supplying means, and means operable by the approach of the workpiece toward said pivoted member for supplying lubricant to said pivoted member and through the feed orifice thereof.

JOHN W. KELSO.
